UNITED STATES PATENT OFFICE

GEORGE T. BELL, OF COLUMBUS, OHIO.

WINDOW CONSTRUCTION.

1,413,377.

Specification of Letters Patent. Patented Apr. 18, 1922.

Application filed March 3, 1921. Serial No. 449,474.

To all whom it may concern:

Be it known that GEORGE T. BELL, a citizen of the United States, residing at Columbus, in the county of Franklin and 5 State of Ohio, has invented certain new and useful Improvements in Window Construction, of which the following is a specification.

This invention relates broadly to an improved structure for effecting the retention of transparent panels within a supporting frame, and has particular reference to an improved mechanical structure whereby glass window panes may be securely and 10 removably mounted within the sash frames of window constructions.

The primary object of the invention resides in the provision of a simple yet efficient construction which is operable for the 15 purpose of effecting the retention of window panes in positions of application within window sash constructions in a positive yet removable manner without involving the use of putty or other similar substances now 20 generally employed for this purpose, the present invention including a retaining structure for window panes which will permit the latter to be readily removed from the sashes or swung to positions disposed 25 angularly thereof, in order that both inner and outer surfaces of the pane will be rendered conveniently accessible from within a building or room for the purpose of facilitating the cleaning or washing thereof.

30 For a further understanding of the invention, reference is to be had to the following description and to the accompanying drawing, in which similar characters of reference denote like and corresponding 35 parts throughout the several views thereof.

In said drawing:

Figure 1 is a fragmentary front elevation of a window sash, and disclosing more particularly the construction comprising the 45 present invention for retaining a transparent panel within said sash,

Figure 2 is a vertical sectional view taken along the plane disclosed by the line 2—2 of Figure 1,

50 Figure 3 is a similar view disclosing the transparent panel of the sash in a position affording access to both sides thereof.

Figure 4 is a detail view of one corner of the retaining frame, and

55 Figure 5 is a detail view of one corner of the transparent panel.

Referring more particularly to the details of the invention, the numeral 1 designates generally a window sash, which is formed to include the usual vertical bars 2 and the top 60 and bottom bars 3 and 4 respectively, the said bars being assembled in any suitable manner to produce the usual rectangular frame construction and to define, within the boundaries thereof, the usual opening 5 for 65 the reception of a transparent panel or window pane 6.

In order to provide an improved mechanical structure for effecting the removable retention of the panel 6 within the opening 5 70 and particularly to avoid the use of putty or the like, the present invention utilizes a strip 7, which is adapted to be secured to the walls of the opening 5, adjacent to the outer portion of the sash and situated in 75 such manner that a rigid shoulder or face 8 will be presented to the interior of the sash. It will be understood that it is within the province of the invention to form the strip 7 integral with the bars of the sash if such 80 a construction is found desirable. Arranged to engage the shoulder 8 is a rectangular gasket 9, which is situated so as to form a base for the reception of the marginal edges of the panel 6, and, in this instance, the 85 upper and lower edges of the panel are provided with substantially U shaped, relatively soft metal strips 10 which are disposed to engage with the gasket 9 and provide means for securing longitudinally extending rods 11 in connection with the upper and lower edges of the panel.

The rods 11 are provided with longitudinally projecting ends 12 which, as shown in Figures 1 and 3, are designed to be positioned within vertical slots 13, which are formed in the side bars 2 of the window sash and extend throughout the height of the opening 5, the upper and lower ends of said slots being terminated in laterally disposed portions 14, which render the vertical portions of the slots accessible from the inner side of the sash, as will be clearly understood. Thus, in positioning the panel 6, the projecting ends of the rods 11 are first 95 inserted into the laterally extending portions of the slots 13, in order that the panel may be moved bodily and laterally into engagement with the gasket 9, and in order that the ends 12 will be positioned in registration with the vertically extending portions of the slots. Then, the panel is re- 100 105 110

tained in this position of application by means of a securing frame 15, which is formed so as to fit within the boundaries of the opening 5, and to snugly engage with 5 the inner edges of the bars of the sash, the said frame having its upper and lower portions formed with extensions 16, which are capable of entering the lateral portions 14 of the slots 13, in order that when the retaining 10 frame has been finally positioned in securing relation with respect to the panel, the inner surface of the sash will present a neat and finished appearance. Preferably, a gasket 17 is situated between the panel 6 and 15 the frame 15, in order to provide a weather tight joint and to eliminate rattle in the final construction. Any suitable means may be employed for holding the retaining frame in its applied position, such for example as 20 fastening elements 18, which are capable of passing through the sides of the frame 15 and entering the vertical bars 2 of the sash 1.

By means of this construction it will be apparent that a window pane may be positively and effectively retained in connection 25 with a window sash or other frame, since the invention is not limited in its scope to window sash constructions per se. When finally assembled the glass panel will be firmly and 30 securely held against rattle or accidental displacement, and more essentially the use of putty and other similar securing compositions will be precluded. A desirable feature accompanying the use of this structure rests 35 in the fact that the window pane may be conveniently adjusted for the purpose of effecting the cleaning or washing of both sides thereof from within a building. This feature may be readily carried out by re- 40 moving the frame 15, and thence by means of the depression 19, the under edge of the panel may be engaged so that the panel may be swung inwardly so that the panel as a whole will assume substantially the inclined 45 position disclosed in Figure 3, the upper projections of the rods 11 being retained within the slots 13, and serving as pivots for permitting of the oscillation of the panel as a whole.

50 What is claimed is:

1. A window sash comprising vertical and horizontal bars connected together to produce an opening, shoulders provided around said opening, a glass panel removably positioned within said opening and having the marginal edges thereof engaging said shoulders, members projecting from the upper and lower edges of said panel into substantially vertical slots provided in the side 55 bars of said sash, and a retaining frame removably positioned within said sash opening and maintaining said panel in secured

relation between said shoulders and the inner surfaces of said frame.

2. A window sash comprising vertical and 65 horizontal bars secured together to define a glass receiving opening, a continuous shoulder around said opening, a glass panel positioned within said opening and having the marginal edges thereof resting against said 70 shoulder, studs projecting longitudinally from the upper and lower corner edges of said panel and received within vertical slots provided in the inner faces of said vertical bars, said slots having the upper and lower 75 ends thereof terminated in lateral entrance extremities, and a retaining frame situated within said opening and engaging with said panel to removably retain the latter within said sash. 80

3. In a window sash, vertical and longitudinal bars secured together to define a glass receiving opening, shoulders around said opening, a removable glass panel occupying said opening and having the edges 85 thereof in engagement with said shoulder, rigid members projecting longitudinally from the upper and lower corner edges of said panel, said members being received within vertical slots provided in the inner 90 faces of said vertical bars, said slots terminating at their upper and lower ends in lateral entrance portions, and a retaining frame removably carried by said sash and engaging with said panel to retain the latter 95 within said sash, said frame being provided with extensions receivable within the entrance openings of said slots.

4. In a window sash, vertical and horizontal bars secured together and forming a 100 glass receiving opening, stationary shoulders around said opening, a glass panel arranged within said opening and having the edges thereof in engagement with said shoulders, U shaped strips carried by the upper and 105 lower edges of said panel, rods extending longitudinally of said panel and retained in connection therewith by said strips, the ends of said rods being formed to project longitudinally beyond the vertical edges of 110 said panel, the vertical bars of said sash including vertically extending slots having lateral entrance openings formed at the upper and lower ends thereof, said slots and entrance openings being situated to receive the 115 projecting ends of said rods, and a retaining frame removably carried by said sash and situated to engage said panel to removably maintain the latter within said sash, said frame being provided with extensions closing the entrances of said slots. 120

In testimony whereof I affix my signature.

GEORGE T. BELL.
